US0D1104948S

(12) **United States Design Patent** (10) **Patent No.:** **US D1,104,948 S**
Guo (45) **Date of Patent:** **** Dec. 9, 2025**

(54) **UNIVERSAL BATTERY FOR ELECTRONIC CIGARETTE**

(71) Applicant: **Shenzhen Greensmoke Technology Co., Ltd., Guangdong (CN)**

(72) Inventor: **Lantian Guo, Shenzhen (CN)**

(**) Term: **15 Years**

(21) Appl. No.: **29/935,259**

(22) Filed: **Mar. 31, 2024**

(30) **Foreign Application Priority Data**

Jan. 27, 2024 (CN) 202430056323.7

(51) **LOC (15) Cl.** **13-02**

(52) **U.S. Cl.**

USPC **D13/103; D27/162**

(57) **CLAIM**

The ornamental design for a universal battery for electronic cigarette as shown and described.

DESCRIPTION

FIG. 1 is a front perspective view of a universal battery for electronic cigarette, showing my new design;

FIG. 2 is a rear perspective view thereof;

FIG. 3 is another front perspective view thereof;

FIG. 4 is another front perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines in the drawings depict portions of the universal battery for electronic cigarette that form no part of the claimed design.

1 Claim, 10 Drawing Sheets
